No. 635,289.

Patented Oct. 24, 1899.

E. J. BARRY.
BUTTER PRINT AND CUTTER.

(Application filed Mar. 24, 1899.)

(No Model.)

UNITED STATES PATENT OFFICE.

EDWARD J. BARRY, OF HARTFORD, CONNECTICUT.

BUTTER PRINT AND CUTTER.

SPECIFICATION forming part of Letters Patent No. 635,289, dated October 24, 1899.

Application filed March 24, 1899. Serial No. 710,395. (No model.)

To all whom it may concern:

Be it known that I, EDWARD J. BARRY, a citizen of the United States, residing at Hartford, in the county of Hartford and State of Connecticut, have invented a new and useful Improvement in Butter Prints and Cutters, of which the following is a specification.

This invention is a combined butter print and cutter, the object being to provide an exceedingly cheap, simple, and efficient device for making the butter into small prints and cutting the same off into lengths suitable for table use.

Another object of the invention is to provide a device which shall be exceedingly easy to operate, it being only necessary to turn a crank to perform all the various functions.

With these objects in view the invention consists, essentially, of a cylinder mounted in a suitable support and having a plunger working therein, said plunger being fed through the medium of a screw-rod and sleeve working thereon, said screw-rod being operated by means of a crank carrying the cutter-blade, said cutter-blade also operating to lift the print-block, which normally closes the forward end of the cylinder and against which the butter is pressed for the purpose of making the desired impression.

The invention consists also in certain details of construction and novelties of combination, all of which will be fully described hereinafter and pointed out in the claims.

In the drawings forming part of this specification, Figure 1 is a perspective view of the device constructed in accordance with my invention. Fig. 2 is a vertical longitudinal section on the line 2 2 of Fig. 1, the print-block being elevated by means of the cutter-blade. Fig. 3 is a transverse section on the line 3 3 of Fig. 2, showing the sleeve and cylinder in section. Fig. 4 is a top plan view of the cutter-blade and attached parts.

In carrying out my invention I employ a cylinder A, supported at its forward end in a short standard B and at its rear end in a standard B', said standards B and B' being rigidly attached to the base C. The standard B has a circular opening into which the end of the cylinder is fitted, said cylinder being provided with an annular collar A', which rests against the inner face of the standard to act as a

stop to prevent the cylinder being projected through the standard. The rear standard B' has an opening cut therein and in which the 55 rear end of the cylinder rests, being held in place by means of hinged cross-piece B². The rear standard B' is made angular in shape, and the front standard has a lateral extension at one side, and in this lateral extension and 60 the extreme rear portion of the standard B' is journaled a threaded shaft D, upon which works a sleeve E, said sleeve having a spring-actuated tongue E', which engages the thread of the shaft, so that when the shaft is rotated 65 the sleeve will be moved along said shaft, and by disengaging the spring-tongue from the threads of the shaft the sleeve can be readily moved back and forth upon the shaft, as described, without rotating said shaft. 70

A piston F is arranged within the cylinder and is connected to one member of a U-shaped operating-rod G, the other member of said rod being connected to the sleeve E, working upon the threaded shaft D, so that 75 as the shaft is rotated the sleeve will move upon the said shaft and cause the piston to move within the cylinder, it being understood, of course, that the cylinder is first filled with butter and the piston inserted in the rear 80 end thereof, and the sleeve will of course be located upon the extreme rear end of the shaft D.

A guide-roller H is mounted upon the base C to the rear of the standard B' and serves 85 as a guide for the operating-rod. In order to rotate the threaded shaft D, I attach a crank-arm I to the forward end thereof and upon the forward face of the standard B, said crank-arm having a handle I' and about midway its 90 length is shaped into a cutting-blade K for the purpose of cutting off a definite quantity of butter fed from the cylinder by means of the piston F, the cutting-blade K being so arranged that at each revolution of the crank-arm it will sever a thin piece of butter which projects from the forward end of the cylinder. 95

A spring-block L is pivoted at its upper end between ears carried upon the upper end of the standard, said print-block being normally held over the forward end of the cylinder by means of a spring L', so that the butter in being forced against said block will receive an impression. As the crank-arm is 100

moved forwardly the print-block is elevated by means of the said arm, the end of said block being beveled, as shown at L^2 , and the crank-arm also has a beveled face I^2 , which 5 engages the said beveled face L^2 , thereby lifting the print-block forwardly and outwardly, as most clearly shown in Fig. 2. In this manner the print-block is lifted away from the end of the cylinder just prior to the cutting 10 operation and is thrown back sufficiently to clear the way for the operation of the crank-arm, and after said crank-arm has passed the spring will immediately return the block to its normal position. These operations are 15 continued until all of the butter has been fed through the cylinder. The spring-tongue of the sleeve is then withdrawn from the threads of the shaft and the sleeve slid rearwardly upon said shaft, thereby withdrawing the piston 20 from the cylinder, and the cylinder can be removed from its support and refilled, thus placing the machine in readiness for continuation of the operation already described.

It will thus be seen that I provide an 25 exceedingly cheap, simple, and efficient machine for shaping and cutting butter into prints of a predetermined size.

Having thus fully described my invention, what I claim as new, and desire to secure by 30 Letters Patent of the United States, is—

1. In a machine of the kind described, the combination with the cylinder arranged upon a suitable support of a **U**-shaped rod carrying a piston, said piston operating in the cylinder, a sleeve carried by the free end of the rod and a threaded rod adapted to engage the interior of the sleeve and operate the piston, substantially as described.

2. In a machine of the kind described, the 40 combination with the cylinder suitably supported, of a piston working therein, a spring-pressed print-block pivoted above and adapt-

ed to normally close the forward end of the cylinder and the crank carrying a cutting-blade adapted to elevate the mechanism for 45 feeding the piston, substantially as described.

3. In a device of the kind described, the combination with a cylinder, a reciprocating rod connected to said piston at one end, a threaded sleeve carried by the other end of the rod, a longitudinally-arranged threaded rod engaging said sleeve, a spring-pressed print-block pivoted above and adapted to normally close the cylinder, and a lever secured on one end of the threaded rod, and having 50 a reduced portion intermediate its ends to form a cutting edge, said crank being adapted to raise the print-block at each revolution thereof, substantially as described.

4. In a machine of the kind described, the 60 combination with the cylinder mounted upon a suitable support, of the spring-actuated print-block pivoted to the forward end of the support and adapted to normally close the forward end of the cylinder, the piston adapted 65 to work in said cylinder, a **U**-shaped piston-rod, one end of which is attached to the piston, the threaded shaft and the sleeve working thereon, said sleeve having a spring-actuated tongue adapted to engage the thread of the 70 shaft, said sleeve being connected to the other end of the **U**-shaped operating or piston rod, a crank-arm mounted upon the end of the threaded shaft and adapted to rotate same, said crank-arm carrying the cutting-blade 75 and handle, said handle having a bevel face adapted to engage the bevel end of the print-block, substantially as and for the purpose described.

EDWARD J. BARRY.
